[57] CLAIM

The ornamental design for a battery storage tray, as shown and described.

DESCRIPTION

FIG. 1 is a top perspective view of a battery storage tray showing our new design;

FIG. 2 is a right side elevational view of a battery storage tray showing our new design on an enlarged scale, the left side elevational view being a mirror image except for the wing nut;

FIG. 3 is a front end elevational view thereof, the rear end elevational view being a mirror image except for the wing nuts;

FIG. 4 is a top plan view thereof;

FIG. 5 is a bottom plan view thereof.

The broken line showing throughout the drawing figures is included for the purpose of illustrating environmental elements only and forms no part of the claimed design.

FIG. 1

FIG. 2

FIG. 3**FIG. 4**

FIG. 5
